UNITED STATES PATENT OFFICE.

JAMES WATSON MAUPIN, OF STUARTS DRAFT, VIRGINIA.

RURAL-CARRIER'S ROUTING DEVICE.

1,037,788.

Specification of Letters Patent. Patented Sept. 3, 1912.

Application filed May 7, 1912. Serial No. 695,789.

To all whom it may concern:

Be it known that I, JAMES WATSON MAUPIN, a citizen of the United States, residing at Stuarts Draft, in the county of Augusta 5 and State of Virginia, have invented certain new and useful Improvements in Rural-Carriers' Routing Devices; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in routing devices for rural mail delivery and comprises a simple and efficient device of this nature having various 20 details of construction and combinations and arrangements of parts which will be hereinafter fully described, shown in the accompanying drawings and then specifically defined in the appended claims.

I illustrate my invention in the accompanying drawings, in which:

Figure 1 is a side elevation of my device. Fig. 2 is a top plan view. Fig. 3 is a cross sectional view on line 3—3 of Fig. 2, and 30 Fig. 4 is a sectional view on line 4—4 of Fig. 1.

Reference now being had to the details of the drawings by letter, A designates a plate from which rises a standard O having 35 serrations O' upon the inner face thereof. Said plate has a dove-tailed slot or recess F formed in the upper surface thereof in which an adjustable dove-tailed block H is mounted. A screw I is fitted in an aperture 40 in said block and adapted to engage a threaded aperture in the plate J mounted in the bottom of said recess, affording means whereby the block may be held in different adjusted positions. Rising from the block 45 is a standard B with serrations D upon the inner face thereof, said standard being vertically disposed with its inner edge parallel to the adjacent edge of the standard O. A follower, designated by letter N, is recessed 50 at N' to receive the two standards and guided by said standards as the follower is raised and lowered. A block Q is provided which has slotted ends Q' adapted to receive 55 said standards and said block has horizontal slots R in which the flanges S of the casings S' are adapted to be guided, said casings

containing a spring-pressed pawl T. By the provision of this particular detailed construction of mounting the casing, it will be understood that the standards may be adjusted different distances from each other and the pawls accordingly so that they may engage the notches upon the adjacent edges of the standard.

It will be noted that each slot in the block 65 carries a spring-pressed pawl, each being adapted to engage teeth upon the adjacent standard. Said block Q is provided with a central aperture for the reception of the pin P which rises from the follower and a 70 knob W at the top of said pin is adapted to limit the upper movement of said block. A spring X is mounted upon said pin and interposed between the follower and block and serving to hold the follower under pressure 75 against the articles of mail beneath.

The operation of my device will be readily understood and is as follows:—The space between the standards being adjusted to desired width, the papers, letters and other 80 articles of mail are placed between the standards and the follower is placed upon the standards in the manner shown in Fig. 1. By pressing down upon the block, the follower will compress the articles into a 85 compact pile intermediate the standards, the pawls engaging the ratchet teeth or serrations upon the adjacent edges of the standards, thus securely holding the mail in a compact form. As the follower is held 90 yieldingly against the pile of articles of mail, when one article is withdrawn, the resiliency of the spring will cause the follower to hold the other articles securely in place.

By the particular construction shown, it 95 will be noted that the apparatus may be adjusted to different widths to accommodate letters, parcels and other articles.

What I claim to be new is:—

1. A routing device for rural mail carriers, comprising a plate, a fixed and an adjustable standard mounted thereon and each provided with serrations upon their adjacent edges, a follower with slotted ends adapted to engage said standards, a block, 105 a spring interposed between the same and the follower, and dogs carried by the block and adapted to engage said teeth, as set forth.

2. A routing device for rural mail carriers, comprising a plate, a fixed and an adjustable standard mounted thereon and each 110

- provided with serrations upon their adjacent edges, a follower with slotted ends adapted to engage said standards, a pin projecting from the follower, a block through which said pin projects, a spring interposed between the block and follower, and dogs mounted upon the block and adapted to engage said teeth, as set forth.
3. A routing device for rural mail carriers, comprising a plate, a fixed and an adjustable standard mounted thereon and each provided with serrations upon their adjacent edges, a follower with slotted ends adapted to engage said standards, a pin projecting from the follower, a block through which said pin projects, a spring interposed between the block and follower, and dogs adjustably held upon said block and adapted to engage said teeth, as set forth.
4. A routing device for rural mail carriers, comprising a plate, a fixed and an adjustable standard mounted thereon and each provided with serrations upon their adjacent edges, a follower with slotted ends adapted to engage said standards, a pin projecting

from the follower, a block through which said pin projects, a spring interposed between the block and follower, spring-pressed dogs, casings in which the same are mounted, and projections upon said casing movable in slots upon said block, as set forth.

5. A routing device for rural mail carriers, comprising a plate, a fixed and an adjustable standard mounted thereon and each provided with serrations upon their adjacent edges, a follower with slotted ends adapted to engage said standards, a pin projecting from the follower, a block having an aperture therein for the reception of said pin; a spring interposed between the block and follower, a knob upon the pin, said block having slots therein, a casing movable in each slot, and a spring-pressed dog in each casing, as set forth.

In testimony whereof I hereunto affix my signature in the presence of two witnesses.

JAMES WATSON MAUPIN.
